United States Patent

Des. 237,957
Patented Dec. 9, 1975

237,957

AIRCRAFT

Lawrence Bernard Rellis, Miami, Fla.
(2209 W. Villa Maria Drive, Phoenix, Ariz. 85023)

Filed Apr. 4, 1974, Ser. No. 457,993

Term of patent 14 years

Int. Cl. D12—07

U.S. Cl. D12—78

Eg-2

FIG-6

FIG-7

FIG. 1 is a top perspective view of an aircraft, showing my new design;

FIG. 2 is a top plan view thereof;

FIG. 3 is a bottom plan view thereof, with the wings in the retracted position;

FIG. 4 is a side elevational view of the aircraft of FIG. 1;

FIG. 5 is a side elevational view thereof, showing the opposite side;

FIG. 6 is a front elevational view thereof; and

FIG. 7 is a rear elevational view of the aircraft of FIG. 3.

I claim:

The ornamental design for an aircraft, as shown and described.
